INVENTOR
Denzil C. Dyer
BY
Adam E. Fisher

ATTORNEY

UNITED STATES PATENT OFFICE.

DENZIL C. DYER, OF BEND, OREGON.

CAMP STOVE.

Application filed May 19, 1921. Serial No. 470,752.

To all whom it may concern:

Be it known that I, DENZIL C. DYER, a citizen of the United States, residing in the city of Bend and State of Oregon, have invented new and useful Improvements in Camp Stoves, of which the following is a specification, reference being had to the accompanying drawings.

This invention is in the way of a collapsible camp stove, and one of the objects is to provide a simple and efficient stove of this kind which may be quickly set up for use or knocked down for transportation. Another object is to provide a draft deflecting set of dampers designed to first send the smoke of the freshly kindled fire directly out of the flue, and then after the heat of the fire develops, to direct the currents of hot air first forwardly and then up and back over the oven so as to completely envelop the oven and quickly cook the food therein.

In the drawings:

Figure 1 is a top plan view.

Figure 2 is a bottom plan view.

Figure 3 is a front elevation, showing the fire door and oven door both partly open.

Figure 4 is a rear elevation.

Figure 5 is a detail view of the interior oven floor and attached damper elements.

Figure 6 is a vertical sectional view of the camp stove on a reduced scale.

In carrying out the invention as embodied in the present form of construction, I provide a rectangular, sheet metal box or stove casing 1, including a top plate 2 having depending side flanges 3 with key holes 4 cut therein adapted to engage the studs 5 set along the upper edges of the side plates 6, and thus releasably lock the top and side plates together. A rear plate 7 is hinged to the top plate 2 at the points 8, and is thus adapted to turn down as a closure for the back of the stove casing. As an additional fastening hooks 9 are pivoted at 10 to the rear plate 7 and adapted to enter slots 11 formed in the extended edges of the side plates. A flue or pipe hole 12 is cut through the back of the top plate. Oven supporting brackets 13 are horizontally mounted on the inner faces of the side plates 6 and their ends are extended frontally to form door supporting lugs 14, and pivotally mounted thereon are the oven and fire doors 15 and 16 which are pivoted together by the

rod 17, the ends of the latter engaging the lugs 14 as stated. An oven floor 18 with frontal and rear dampers 19 and 20 hinged thereto at 21 and 22 is loosely laid on the brackets 13, and with the dampers laid flat these elements are co-extensive with the inside length of the stove casing. A damper rod 23 is pivoted at 24 to the rear damper 20 and extends forwardly to engage the frontal damper 19 through a loop 25 in the rod passed into a slot 26 in the damper. The relation of the loop 25 to the pivotal point 24 is such that when the damper 20 is laid flat or closed the loop 25 is adapted to hold the damper 19 upright. Similarly the frontal damper 19 may be laid flat or closed, and the rear damper 20 opened by means of the damper rod 23. The end of this rod extends out through a hole 27 in the oven door 15.

In use the food to be cooked is placed in any suitable pan and the latter then slid into the oven. When the fire is started the rear damper 20 is opened and the frontal one 19 is closed, thus throwing the smoke directly out the flue hole 12, but after heat is generated same may be directed forwardly and over the contents of the oven by closing the rear damper and opening the frontal one. The stove may be readily knocked down and compactly packed for transportation. The space below the oven plate and the dampers constitute the combustion chamber and the fire is built within the combustion chamber upon the ground, the stove being open at the bottom for this purpose. In Figure 6 of the drawings both chambers are shown raised in dotted lines for the purpose of illustration but in practice the rear chamber will be raised when the fire is first started and the front damper will then be closed so that the smoke will pass directly out through the opening 12 in the top plate. After the smoke has passed out and the fuel burned to hot coals the rear damper is closed and the front damper is raised to cause the heat to travel forwardly to the opening formed by raising the front damper and then upwardly through such opening and rearwardly over the top of the oven plate to the opening 12 thereby subjecting the articles of food placed on the oven plate to both the heat of the fire below the oven plate and to the heat passing over the oven plate. The upper or oven door 15

is opened for the purpose of engaging the loop or bend 25 of the damper operating rod with the slot 26 of the front damper.

When it is desired to collapse the stove 5 the flanges 3 of the top plate are disengaged from the studs 5 of the side plates, the key holes 4 permitting the side plates to be readily moved inwardly when the enlarged portions of the key holes are brought 10 opposite the heads of the studs. The top plate may then be lifted off the said plates and the hinged rear plate may be swung flat against the top plate. As the ends of the pivot 17 of the oven and fire doors are supported in openings in the projecting lugs 14 the doors may be readily removed and laid with the side plates upon the top plate and the rear plate and the oven plate and the 15 dampers are then arranged upon the collapsed portions of the stove. This will enable the stove to be compactly arranged for 20 shipping or storing.

While I have herein described a certain specific method of constructing and assembling the elements of my invention, it is understood same may be varied in minor details, not departing from the spirit of my invention as defined in the appended claims.

I claim:

30 1. A collapsible camp stove, comprising

top, side, back and front plates and means for detachably securing same together to form a stove casing, the front plate being formed of an upper oven door and a lower fire door hinged together and each adapted 35 to open outwardly; an oven floor, substantially less than the length of the stove, medially and detachably mounted within the stove casing; a front and a rear damper hinged respectively to the front and rear 40 ends of the said oven floor and adapted to turn upwardly; a damper rod pivoted to the rear damper and extended forwardly through the oven door section of the front plate and having a hook to releasably engage the frontal damper; and a flue hole cut through the back end of the top plate.

2. In a collapsible camp stove, an upper oven door and a lower fire door hinged together to form the front of the stove; a relatively short oven floor within the stove and aligned with the hinge of the said doors; dampers hinged to the front and back of the oven floor; and means for manipulating the said dampers.

DENZIL C. DYER.
